ARC-LAMP.

1,136,593.

Specification of Letters Patent.

Patented Apr. 20, 1915.

Original application filed March 6, 1905, Serial No. 248,549. Divided and this application filed June 19, 1913. Serial No. 774,685.

To all whom it may concern:

Be it known that we, RICHARD FLEMING and CROMWELL A. B. HALVORSON, Jr., citizens of the United States, residing, respectively, at Indianapolis, county of Marion, State of Indiana, and at Saugus, county of Essex, State of Massachusetts, have invented certain new and useful Improvements in Arc-Lamps, of which the following is a specification.

This application is a division of our prior application, Serial No. 248,549, filed March 6, 1905, and the invention relates to arc lamps, and more particularly to arc lamps in which the electrodes employed are of such a character that a flaming or luminous arc is obtained.

We have found that, with electrodes so arranged that the axis of the arc is vertical, as in the ordinary case, it is sometimes highly desirable to produce air currents which pass downward by the arcing surface or end of the upper electrode.

By a suitable proportioning and arrangement of parts, a down draft by the lower end of the upper electrode and an up draft along the upper end of the lower electrode is obtained. Such an arrangement tends to steady the arc at both ends, thus rendering the light-giving arc more stable.

In many flaming arc lamps, with or without the draft conditions above indicated, the electrodes are normally out of contact and the arc is established by bringing the electrodes together and then separating the same a certain definite distance. This arrangement is usually, though not always, made in lamps which are operated by constant alternating currents, and we have found that in such lamps the use of a compensator intermediate between the line and the lamp mechanism proper is particularly useful; and it is the employment of such compensator in cooperation with such and other lamps that constitutes the subject of this divisional application. The construction of the lamp, by which the draft conditions above indicated are secured, is specifically claimed in our parent application of which this is a division.

In the drawings which constitute a part of this specification, Figure 1 is a per-

spective view of an arc lamp with the casting and globe removed; Fig. 2 is a plan view showing one of the clutches employed in the lamp; Fig. 3 is a sectional elevation of the lamp shown in Fig. 1, with some of the parts removed to facilitate the understanding of the structure, and Fig. 4 is a diagram showing the compensator and circuit arrangements of the lamp.

Referring to the drawings and now particularly to Figs. 1, 2 and 3, 1 represents the hood or top member of the lamp. The hood or top member comprises a horizontal portion 2 from the lower end of which a tubular extension 3 projects. Means, such as the pulley 4, of insulating material, are carried from the upper side of the horizontal portion by which the lamp may be supported. The tubular extension has openings 5 formed in its upper end for a purpose hereinafter set forth. A shell 6, having its upper end flared, is supported from the extension 3 in such manner that air currents may pass between its inner surface and the outer surface of the extension 3. The upper end of the shell 6 terminates slightly above the lower end of the aperture 5. A shell member 7 surrounds the horizontal portion 2 of the member 1, to which it is secured by screws 8.

The lower end of the tubular extension 3 is threaded internally and a tubular member or pipe section 9, externally threaded, is screwed into the lower end of the extension 3. A dish-shaped hood 10 is secured to the upper end of the tubular member 9 just below the end of the extension 3, a threaded aperture being centrally formed in the member 10 in which the member 9 is screwed. The lower end of the member 9, which is externally threaded, has screwed upon it an internally threaded hollow member 11. The member 11 is provided with a horizontally extending flange portion 12 which is circular in outline. The flange portion 12 forms the lower platform of the lamp.

Against the lower end of the lower portion of the member 11, which is bell-shaped, is secured a chambered member 13. In the form illustrated in the drawing, the outer surface of the member 13 is cylindrical, and the member is secured in place by means

of an annular member 14 bearing against the lower end of the member 13 and secured to the lower end of the member 11 by screws or bolts 15 which are threaded into 5 ears 16 formed on the member 11. Suitable means, such as washers 18, formed of insulating material, are employed to insulate the members 11 and 13 from each other. A tubular member or part 19, which may be 10 formed integrally with the body 13, passes diametrically through the latter. The outer shell of the member 13 is apertured at the ends of the tubular part or member 19.

An opening 20 axially located with 15 respect to the outer wall of the member 13, the member 11 and the member 9, is formed in the upper side of the member 19. An electrode casing or tube 21, which may be formed out of sheet metal, is axially placed 20 in the members 9 and 11. The upper end of the tube is about on a level with the upper end of the member 9. The lower end of the tube 21 projects into the opening 20 and is secured in fixed relation to the part 25 19 by a screw 22 passing through a tubular boss 23 projecting from the upper side of the part 19. From the under side of the part 19 a cylindrical flange portion 24, concentric with the shell 21, projects downward. 30 A ring or electrode guide portion 25 may, if desired, be connected to the flange 24 by ribs, though it is frequently dispensed with.

The upper electrode 27 of the lamp slides in the shell 21, which, with the member 19, 35 forms a receptacle for the electrode in which the body of the electrode is protected from the heated gases passing through the chimney. The upper end of the electrode 27 is secured in any suitable manner, as by means 40 of spring clips or the like, to a follower weight 28, which in turn is connected to the upper and closed end of the shell or member 21 by a flexible conductor 28'. The lower end of the electrode 27 which projects out of the 45 lower end of the shell 21 passes through the ring or guide 25. A clutch member 29, provided with an electrode engaging portion 30, is employed for intermittently securing the electrode 27 in fixed relation to the tube 21 50 as the conditions of service demand in a manner hereinafter described. The clutch 29 in the construction illustrated is located in the bore of the part 19 and has one edge supported by lugs 29' from the part 19. 55 The lower electrode 35 of the lamp, which is in axial alinement with the electrode 27, is secured at its lower end in a socket part 36 carried by a bracket 37 secured to the lower end of a tubular member 38 which 60 extends parallel to the electrode. The tubular member 38 slides on a rod 39, the upper end of which is secured to a bracket 40 secured to but insulated from the upper end of the member 9 just below the hood 10. A

rod 41, parallel to the rod 39, has its upper 65 end secured to the bracket 40 and its lower end secured to a member 42, which is secured to but insulated from the flange 12.

A tubular member 43, having its upper end secured in a socket part 45 carried by 70 the member 42, projects downward to a point below the lower end of the member 13. The tubular member 43 surrounds the member 38 and serves as a guide for it. To the lower end of the member 43 is detachably 75 secured an arm 46. The outer end of the arm 46 is formed with a threaded aperture in which is screwed the lower end of a tubular shell or shield 47. This shield or member 47, which is formed of some good heat 80 conducting material, such as copper or brass, is formed with an aperture in which the electrode 35 has a sliding fit. The vertical position of the member 47 may be adjusted by screwing it up or down in the threaded 85 socket in the arm 46.

A cross-head 50 is secured to the upper end of the member 38. The cross-head is formed with an aperture or slot through which the rod 41 passes. The cross-head 90 95 can thus slide upon the rod 41 and serve to prevent angular displacement of the electrode 35 about the line of movement of the member 38. A flexible conductor is employed to electrically connect the bracket 40 and the cross-head 50.

Upper and lower clutches in coöperative relation with the member 38 are located above the flange or platform 12. The yoke member 51 of the lower clutch which surrounds the member 38 is provided with a pivoted pawl 52 normally held in position to lock the lower clutch to the member 38 by a helical spring 53. The lower end of the spring 53 is secured to the outer end of the 100 pawl 52 while the upper end is secured to the bracket 40. The yoke member 54 of the upper clutch, which also surrounds the member 38, has pivoted to it a pawl 55. The outer end of the pawl 55 loosely surrounds a short neck or stem 56 which connects the upper end of the outer member of a dashpot 57 to the lower end of an armature 58. The armature 58, which is U-shaped, is provided with two similar upwardly extending legs 59. Each leg 59 passes axially into the corresponding one of a pair of vertically disposed magnet coils 60. The magnet coils 60 are secured in any suitable manner to the tubular member 115 120 9. In order to strengthen the action of the magnet coils upon the armature, a stationary U-shaped core 61 has its downwardly projecting ends extending into the upper ends of the coils 60. A bow-shaped spring 125 62 secured to the upper side of the yoke member of the armature 58 serves to prevent a violent engagement between the ar-

mature 58 and the lower ends of the coils 60 when energized in a manner hereinafter described.

An extension 63 from the yoke member 51 is formed with an aperture through which passes the upper end of a member 64 which is connected to the outer end of the clutch member 29. A cross pin 65, passing through the upper end of the rod 64 above the extension 63 serves as a means by which after a certain predetermined upward movement of the clutch yoke 51 further upward movement of the yoke will cause the member 64 to be lifted to cause the clutch 29 to release the electrode 27 and allow it to move downward under the action of its weight and that of the followers 28. In the position shown in Fig. 1, with the clutch member 51 down, there is no engagement between the extension 63 and the cross pin 65, and the clutch member 29 is held by its own weight and that of the member 64 in the position in which it locks the electrode 27 in fixed relation to the tube 21.

25 A solenoid magnet coil 70, with its axis vertically disposed, is secured to the member 9 in any suitable manner, as by means of screws 71 which pass through extensions from the end pieces 72 of the magnet. An outwardly turned portion from the extension of the lower end piece 72 forms a bracket 72' upon which a contact piece 73 is supported. The contact piece 73, which may be in the form of a short section of a carbon pencil, is insulated from the bracket. A movable armature or core passes axially into the bore of the coil 70. The lower end of the armature carries a contact member 74, which may also be in the form of a section of carbon pencil. When the coil 70, which is in series with the arc between the electrodes 27 and 35, is not energized by the proper current, the contact member 74 engages and rests on the contact 73, but, when the coil 45 is operatively energized, the contact 74 is held out of engagement with the contact member 73 as shown in Fig. 3 of the drawings.

The lamp construction shown in Figs. 1, 50 3 and 4 is primarily intended for operation with alternating current. When the alternating current for operating the lamp comes from a constant current system, we employ in accordance with our invention a compensator or auto-transformer 75, which is supported from the member 9 by brackets in any suitable manner.

The casing 77 is hung from the hood member 10 in the usual manner as by screws 60 78. The lower end of the casing 77 closely embraces the periphery of the flange 12. This casing serves to protect the lamp mechanism located between the hood 10 and the platform 12. Suitable apertures 79 guarded by

a shield 80 are provided for admitting air 65 for ventilating purposes to the interior of the casing. An annular extension from the casing 77 is secured to the lower end of the latter. The lower end of the extension 81, which flares outward, has secured to it two 70 toothed members 82. A disk-shaped member 84 is secured against the lower surface of the member 14 by screws 85, which are screwed into openings in ears 86 formed for the purpose on the member 14. The disk-shaped member 84 is formed with an aperture 87 which registers with the opening in the member 13. A globe 90 inclosing the electrode 35 is held against the under side of the outer edge of the member 84 by bails 80 or hooks 91 carried by a collar 92 secured to the upper end of the globe 90. Each of the bails 91 hooks over one of the teeth on the corresponding toothed member 82. In order to get a tight joint between the upper end 85 of the globe 90 and the member 84, a gasket or washer 93 of any suitable material may be employed.

In Fig. 4, we have shown a diagram of the compensator and circuit arrangement which 90 we employ in operating our lamp from a constant alternating current circuit. In the diagram, 95 and 96 represent the lamp terminals which are connected into the external circuit. Conductors 97 and 98 connect the 95 terminals 95 and 96 respectively to the points 99 and 100 in the winding 101 of the compensator 75. One terminal of the coils 60, which are connected in series with each other, is connected to the line 97 at the point 100 102. The other terminal of the coil 60 is connected to the contact member 74. The contact member 73 is connected to the conductor 98 by a conductor 103. One end of the effective portion of the winding 101 is 105 connected to the electrode 35 by a conductor 104. The other end of the effective portion of the compensator winding is connected to one of the terminals of the winding of the magnet 70 by conductor 105. The other terminal of the winding of the coil 70 is connected to the electrode 27.

In the out-of-service condition of the lamp which is shown in Fig. 1, the coils 60 are deenergized and the armature 58 is in its 115 lowest position, the electrodes 27 and 35 being separated. Similarly the winding of the coil 70 is deenergized and the contacts 73 and 74 are in engagement. On connecting the lamp in circuit, current begins to 120 flow through the circuit which includes the conductor 97, windings of the coil 60, contact members 74 and 73, conductor 103 and conductor 98. This causes the armature 58 to be elevated. The elevation of the armature 58 causes the electrode 35 to be raised through the action of the upper clutch on the tubular member 38. As the tubular

member 38 is moved upward, the lower clutch member will, under action of the spring 53, move with it until the pawl 52 engages a stop 52' adjustably secured to the 5 rod 41, after which further upward movement of the member 38 will not produce a corresponding movement of the lower clutch member. As the lower clutch member approaches the upward limit of its movement, 10 the cross-pin 65 is engaged and the clutch member 29 operated to release the upper electrode which thereupon starts to fall into engagement with the lower electrode. When the electrodes 35 and 27 come together current begins to flow between them through a circuit which includes the entire compensator winding 101, conductor 104, winding of the coil 70, electrodes 27 and 35 and conductor 105. The passage of current through 15 the coil 70 causes the armature to be raised, thus separating the contacts 74 and 73 and opening the circuit through the coils 60.

In the ordinary case in which a portion of the lower electrode has been consumed 20 since the preceding feeding operation, the member 38 is pulled through the yoke 51 of the lower clutch member far enough at each feeding operation to compensate for the electrode consumption since the previous feeding 25 operation before an operative contact is established between the two electrodes and sufficient current flows through the windings 30 to cause the separation of the contact members 73 and 74. As soon as the circuit through the coil 60 is broken by the separation of the contact members 74 and 73, the electrode 35 begins to descend under the action of gravity, thus drawing an arc between the two electrodes. The dashpot 57 is arranged so as to offer no resistance to the 35 upward movement of the armature 58, but to prevent a rapid downward movement of the armature, thus insuring a separation of the electrodes slow enough to prevent a rupture 40 of the arc. It will, of course, be understood that after a small initial downward movement of the electrode 35, the lower clutch holder moves out of engagement with the cross-pin 65 and the upper electrode is 45 locked in the tube 21 by the clutch member 29. The downward movement of the lower electrode is checked and the length of the arc struck limited by the engagement of the pawl 52 with a stop 52" formed on the member 40. It will thus be observed that the 55 length of the arc struck after each feeding operation is equal to the play of the pawl 52 between the upper and lower stops 52' and 52", respectively, and is independent 60 of the electrical condition of the lamp.

With the compensator connected as shown in Fig. 4, the voltage between the terminals 95 and 96 is, of course, materially less than the voltage of the arc and the currents in 85 the primary and secondary windings of the

compensator vary inversely. The use of the compensator in the manner described is of particular utility where one of the electrodes, for instance the upper one, is composed of or contains some material like titanium carbid. With such an electrode the arc current is usually materially lower than that of the ordinary lamp giving the same light and using a carbon electrode though the arc voltage may be somewhat higher. The arrangement specified thus facilitates the employment of a lamp with a titanium carbid electrode in existing circuits. 70

Ordinarily, after the arc is struck in the manner described, the lamp operates without feeding until the upper electrode is consumed to such an extent that, in the wandering of the arc, its upper end plays upon the ring 25. When this occurs, rectification of the arc current begins to take place and the arc resistance becomes abnormally high. This either causes the arc to break or reduce the current in the secondary winding of the compensator to such a value that the magnet coil 70 is no longer operatively energized. 80 The contact members 73 and 74 then engage, closing the circuit through the coils 60, whereupon the feeding operation of the lamp is repeated. 85

As the air about the arc in the globe 90 becomes heated by the arc, an ascending current is set up which passes through the draft tube or chimney formed of the member 13, member 11, member 9 and the projection 3 to the atmosphere through the apertures 5. 95 It will be observed that the chimney thus formed is practically unimpeded and extends from the arc to the top of the lamp and is of the maximum length possible in a lamp of the given dimensions. The air 100 moving out of the chamber or globe 90 by slow natural draft through the chimney is replaced by rapidly moving air entering the globe through the tubular member or portion 19. The flange member 24 and concentric ring 25 form an annular contracted nozzle through which the contracted entering air currents pass downward along the lower end of the upper electrode and the arc extending therefrom in the form of an envelop, shell or tubular body of cool rapidly moving air. This moving body of air which has greater velocity than the upward current through the wide unimpeded chimney 110 serves to centralize the arc, particularly its upper end. With this arrangement, the general upward movement of air in the globe and chimney causes an upward movement of air by the upper end of the lower electrode, thus in effect creating an upwardly movable shell or envelop of air surrounding the upper end of the lower electrode. 115

When the electrode containing the light-producing salt or salts is formed wholly or largely of titanium carbid, a tendency to 120

disintegration of the arcing end of the electrode is produced by the heat of the arc. By forcing a comparatively powerful draft of cool air by the arcing end of the electrode, 5 as in the arrangement shown in the drawings, this tendency toward disintegration is practically done away with.

The shield 47 serves to conduct away heat from the lower electrode and thereby reduces its consumption by heat oxidation. Its form and the form of its support 46 serve as a means for shaping the upward flow of air by the lower electrode. The flow of air relative to the upper end of the lower 15 electrode may also be affected by the elevation of the shield 47 in its support.

To release the rod 38 from the clutch members in order to permit trimming of the lamp, or for other purposes, a collar 38' is 20 placed about the rod 38 between the member 42 and the yoke of the lower clutch member. An operating rod 38'' connected at its upper end to the collar 38' extends downward through openings formed for the purpose in the members 42 and 14. By moving the operating rod 38'' upward, the clutches will be forced up into the position in which the pawl of the lower clutch engages the upper stop 51, in which position the rod 38 is released from both clutches and may 25 be lowered.

While in the preceding descriptive matter and in the drawings we have described and illustrated the best forms of our invention 35 now known to us, it will be obvious to those skilled in the art that many changes may be made in the form of our invention without departing from its spirit, and we do not wish the claims hereinafter made to be limited by the embodiment shown and described 40

more than is made necessary by the state of the art.

What we claim as new, and desire to secure by Letters Patent of the United States, is:—

45

1. In an arc lamp for use in a constant current system, a compensator having its primary winding connected in the constant current system, a secondary winding the terminals of which are connected to the electrodes, a winding in shunt around the primary winding of the compensator for feeding the electrodes, and a device in series with the electrodes for opening the shunt circuit when the arc between the electrodes carries 50 a current of normal strength.

2. In an arc lamp for use in a constant current system, a compensator having its primary winding connected in the constant current system, a secondary winding the terminals of which are connected to the electrodes, a magnet and mechanism controlled thereby for feeding the electrodes, and a magnet winding in series with the electrodes for controlling the mechanism controlling 55 magnet.

60

In witness whereof, RICHARD FLEMING has hereunto set his hand this 11th day of June, 1913; and CROMWELL A. B. HALVORSON, Jr., has hereunto set his hand this 16th 65 day of June, 1913.

RICHARD FLEMING.

Correction in Letters Patent No. 1,136,593.

It is hereby certified that in Letters Patent No. 1,136,593, granted April 20, 1915, upon the application of Richard Fleming, of Indianapolis, Indiana, and Cromwell A. B. Halvorson, jr., of Saugus, Massachusetts, for an improvement in "Arc-Lamps," an error appears in the printed specification requiring correction as follows: Page 5, line 46, for the word "damp" read *lamp*; and that the said Letters Patent should be read with this correction therein that the same may conform to the record of the case in the Patent Office.

Signed and sealed this 18th day of May, A. D., 1915.

[SEAL.]

R. F. WHITEHEAD,

Acting Commissioner of Patents.
